CONTAINER

George Arlington Moore, New York, N. Y.

Application February 27, 1943, Serial No. 477,375

2 Claims. (CL 229—14)

The present invention relates to improvements in containers and packages for food products and the like and has particular reference to such articles made from a tubular formation wherein the end closures are hermetically sealed and extend outwardly and downwardly from the container adjacent side walls to which they are ultimately sealed after the particular commodity has been incorporated therein.

The present invention is a continuation-in-part of my copending application filed March 3, 1943, Serial No. 477,821, which is directed to the conversion of packaging materials into laminated and scored tubular formations for shipment in flat condition, subsequently to be erected by the packager into squared cartons, filled with a commodity adapted thereto and made into hermetically sealed packages readily usable by the ultimate consumer.

A principal object of the present invention is the provision of a container or package having end closures with hermetically sealed seams free from surplus infolds and consequent additional thicknesses at the ends of the mouth of the seam which will more efficiently maintain an hermetic seal, utilize the surplus folds of the end extensions by extending them oppositely outwardly, applying to their under surfaces a thermoplastic adhesive and thermally sealing them to their adjacent side panel.

More specifically, it is an object of the present invention to provide end closures in a container or package made from a blank of cardboard reinforcing material having adhesively secured thereto a liner of laminated sheet material which consists of a ply of suitable thermoplastic material and a ply of suitable fibrous material and which extends beyond the edges of the cardboard blank, the same being made into blanks which are scored to define side and end panels and thereafter being formed into a tube providing the same with end closures formed by the end panels with the marginal extension passing between the edges of the end panels where they are thermally united to form an end closure hermetically sealed with extension folds extending beyond and away from the side panel and at right angles thereto and being treated with a thermoplastic adhesive so that they can be affixed to the adjacent side panel.

Other objects of the invention will in part be obvious and will in part appear hereinafter.

The invention accordingly comprises an article possessing the features, properties, and the relation of elements which will be exemplified in the

article hereinafter described and the scope of the application of which will be indicated in the claims.

For a fuller understanding of the nature and object of the invention reference should be had to the following detailed description taken in connection with the accompanying drawing, in which:

Fig. 1 is a plan view of a blank adapted to be folded into tubular formation;

Fig. 2 is an end view of the folded blank;

Fig. 3 is a view similar to Fig. 2 showing a further step in the development of the tubular formation after sealing the blank;

Fig. 4 is an isometric view of the blank in Fig. 3 opened up into squared position;

Fig. 5 is an isometric view showing the manner of manually bringing together the end extensions in the formation of the seam;

Fig. 6 is an end elevation of a fragmentary portion of the upper half of a container, partly in section and illustrating the heat-sealing operation;

Fig. 7 is a view similar to Fig. 6 showing a cross-sectional view of the upper part of a closed package illustrating the direction of fold of the seam;

Fig. 8 is a fragmentary cross-sectional elevation of the upper corner of a container illustrating the application of heat to the under surface of an extended portion;

Fig. 9 is a view similar to Fig. 8 depicting the manner in which the extension is adhesively united to an adjacent end panel or wall; and

Fig. 10 is an isometric view of a completed package.

Referring more particularly to Fig. 1 of the drawing there is indicated generally at 11 a composite blank of material made in accordance with the method set forth in my above mentioned copending application. This composite blank consists of a fibrous blank of material such as, for example, cardboard 12, which is adhesively affixed to a laminated sheet 13 which consists of a web of thermoplastic material or a material which has been surface treated with a thermoplastic material, and a web of fibrous reinforcing material such as paper or the like. It will be observed that the laminated sheet extends marginally beyond the edges of the cardboard blank 12. The resulting composite blank is provided with parallel score lines 14 which define side panels ultimately forming the side walls of a container or package and end panels which form parts of the top and bottom thereof. There are

also provided diagonal score lines 15 which together with a section of one of the parallel score lines define an area which is generally triangular in configuration. That portion of the triangle formed by the section of the parallel line defines the base of the triangle as indicated at 16. It is important to note that for ease and facility in squaring the container and folding the end closures in proper position the score lines are all impressed so that they bulge outwardly with the exception, however, that the base line of the triangular area 16 is oppositely impressed so as to be directed inwardly of the container ultimately to be formed.

It will also be seen that an application of a hot melt adhesive has been made to the cardboard portion by imprinting thereupon such an adhesive in predetermined areas. This is done exactly in the manner set forth in my co-pending application except that a different pattern is used to apply the adhesive in different areas. Marginally along the cardboard an application of such adhesive 17 has been made similarly to that in the parent case. However, the triangular areas defined by the score lines have completely been filled in with such a thermoplastic adhesive as indicated at 18.

Referring now to Figs. 2 to 4 inclusive, it will be seen that the composite blank has been folded upon itself along a suitable median line which is the central one of the parallel line 14 with the thermoplastic sheet of material in face-to-face relationship with respect to itself. The marginal portions, as indicated by the arrows in Fig. 2, are then brought together and by the application preferably of heat and pressure the two marginal portions are welded together, folded over upon a marginal portion of the cardboard blank as indicated in Fig. 3 and thereafter by similar application of heat and pressure which activates the hot melt adhesive 17 the seam is thermally affixed to the marginal portion of the cardboard side wall and a longitudinal seam is formed. As more fully described in my other application, it is in this knocked-down and collapsed form that the resulting tube is shipped to the packer to be erected into squared position as shown in Fig. 4.

It will be observed by reference to Fig. 3 that there might be an optional modification with respect to certain kinds of tubular formations. There is indicated at 19 a tape which can be applied to the longitudinal seam 20 or to overlap the same completely and itself be affixed to adjacent areas of the cardboard side wall. The tape is shown broken off in Fig. 5. This optional form of reinforced container is particularly advantageous in the reinforcement of very large sized containers and particularly those which are to carry commodities such as, for example, paint, oil and other of the heavier liquids. In the case of paint, for example, this tape could be of a color representing the paint within the package. Likewise, for certain types of commodity packing, a tape band could pass around the package on two sides and two ends for decorative and display purposes as well as for additional reinforcement which it will afford.

Referring now to Fig. 5, there is shown the manipulation of the tube for forming the first end closure. The score lines control the break and by pressing with the fingers inwardly the folds will arrange themselves in an orderly fashion with the extending marginal portions of the laminated sheet forming into two parallel lines

in thermoplastic face-to-face relationship as in the case of the longitudinal seam formation, free of gathers or wrinkles. The action of the fingers is practically instantaneous in forming this closure. A single motion of the fingers squeezing the end panels and the extending portions of the tube, together bring about this relationship. It will be seen by reference to Fig. 6 that the end closure for the formation of an hermetically sealed seam in this area can readily be effected. The contracted end of the container can easily be pushed between the sealing irons therein illustrated and the upward thrust of the container will also aid in throwing the end panels of the container down into position whereupon the closing of the sealing irons, because of the heat and pressure applied to the ends of the container, will bring them together thermoplastically and effect an hermetic seal like that shown in Fig. 5. It will be observed that there are no infolds in this end closure formation, as in the case in my copending application. On the contrary, the seam is brought together without any surplus layers of the sheet material between the seam in the end of the mouth opening. Instead of being folded inwardly, the surplus material in the fold is folded outwardly to provide extension 21, which extends outwardly and oppositely away from the adjacent side of the panel. After the formation of this seam the same is folded over in either direction against one or the other of the end panels to form an end closure and because of the application of thermoplastic adhesive 18 within the triangular portion of the cardboard reinforcing blank, as defined by the score lines, the entire end closure can be sealed in this position. This is done by having a hot plate 22 brought closely in contact with the under surface of the fold where the surplus extends away from the carton, as indicated in Fig. 8. The hot plate is so applied as to radiate heat directly into the hot melt adhesive on the triangular under surface. This adhesive is quickly activated so that it is only necessary to press the extending portion downwardly and inwardly against the panel or end wall of the container or package adjacent to it whereby it is securely fastened thereto. The hot melt adhesive sets quickly, in fact almost instantly. The ultimate package shown in Fig. 10 it will be seen provides an end closure which is unlike the end closure in my previous application not thermally sealed across the top, but merely by having the surplus material extend outwardly, applying the adhesive to the under surfaces of the outward extensions and thereafter pressing them in contact with the adjacent panels the end closures are adequately fixed in position.

There are a number of distinct advantages in this type of end closure. For example, the container is supported adequately on all six surfaces with board reinforcement and particularly in times of scarcity can serve as a practical substitute for tin and glass, as is also true of my infolding type of container or package. In addition to this, the simplicity of the seam structure does not require any sealing irons to affix the top of the seam across the end closures and it will be appreciated that very simple types of machinery can be constructed to handle these flat containers at a very high speed.

It will thus be seen that the objects hereinbefore set forth may be readily and efficiently obtained, and since certain changes may be made in the above described article and different em-

bodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A container comprising a blank of reinforcing cardboard material, a laminated sheet of paper and heat-sealable material constituting a liner for said container to make it hermetically sealed, said sheet being of larger area than said cardboard and secured thereto and extending marginally therebeyond, all layers of the resulting composite construction having score lines impressed therein defining front and end panels and top and bottom closure panels, said top and bottom closure panels adjacent said end panels having score lines defining triangular portions, said triangular portions having adhesive applied thereto and a marginal stripe of adhesive applied along one edge of said cardboard, said composite construction being folded upon itself with the heat-sealable material in face-to-face contact and sealed along its extension portion between front and end panels to provide a longitudinal seam, said seam being secured to said marginal stripe of adhesive to provide a tube, top and bot-

tom closures formed by said top and bottom panels being inwardly folded with the heat-sealable material projecting therebetween in face-to-face contact and being heat-sealed and downwardly folded against adjacent panels, said triangular portions containing said adhesive being sealed against said end panels.

2. A container comprising a blank of reinforcing cardboard material, a laminated sheet of paper and heat-sealable material constituting a liner for said container to make it hermetically sealable, said sheet being of larger area than said cardboard and secured thereto and extending marginally therebeyond to provide a composite construction, all layers of the resulting composite construction having crease lines impressed therein and defining front and end panels and top and bottom closure panels, said top and bottom closure panels adjacent said end panels having score lines defining triangular portions, said composite construction being folded with the heat-sealable material in face-to-face contact and sealed along its marginal extending portions between front and end panels to provide a longitudinal seam, said seam being secured in folded over position along an adjacent wall to provide a tube, and top and bottom closures provided by said top and bottom panels being inwardly folded with the heat-sealable material projecting therebetween in face-to-face contact and being heat-sealed and downwardly folded against an adjacent panel with each triangular portion being folded against its adjacent panel and secured in such position.
